UNITED STATES PATENT OFFICE.

EDWARD COURT, OF MILWAUKEE, WISCONSIN.

SPINDLE FOR BOTTLE-WASHING MACHINES.

No. 905,149.

Specification of Letters Patent.

Patented Dec. 1, 1908.

Application filed November 25, 1907, Serial No. 403,613. Renewed October 8, 1908. Serial No. 456,771.

To all whom it may concern:

Be it known that I, EDWARD COURT, a citizen of the United States, residing at Milwaukee, in the county of Milwaukee and State of Wisconsin, have invented certain new and useful Improvements in Spindles for Bottle-Washing Machines, of which the following is a specification, reference being had to the accompanying drawing, forming a part thereof.

This invention relates broadly to improvements in bottle washing machines, but more particularly to improvements in brush spindles employed in such machines.

My invention has for its object the provision in a bottle washing machine employing brushes or like cleaning means, of an improved spindle which acts to compensate for the wear on the brush and to positively force the same into proper contact with the bottle to be cleaned so as to insure effective cleansing of each bottle passed through the machine.

The present improvement is especially adapted for use in those machines wherein the brushes receive only a rotary movement and the bottles are bodily moved to bring them into position to receive the brushes, the bottle carrier receiving a predetermined, limited movement. Through continued use the ordinary brushes wear down or are broken off with the result that they fail to properly contact with and cleanse the bottles and especially the bottoms thereof, which necessitates the frequent removal of the worn brushes and substitution of new ones. By my improvement however this wear is automatically compensated for by the method of mounting the brushes and the construction of the spindles, as will appear hereinafter. The advantages thereby obtained are twofold, increased utility of each brush and the certitude of thorough cleansing in spite of the wear on the brush.

The means by which these objects and advantages are obtained will be more particularly described in the following specification and are illustrated in the accompanying drawing showing the preferred embodiment of my improvement, in which:

Figure 1 is a side elevation of a bottle washing machine, with parts broken away, showing an adaptation of my improved spindle thereto; Fig. 2 is an elevation showing the spindle with brush attached; and

Fig. 3 is a vertical section of the spindle and brush holder.

With more particular reference to the drawing, especially Fig. 2 thereof, a brush 1 of bristles, or other suitable material, is secured by means of a core 2 to a suitable hollow brush-holder 3. As seen in Fig. 3, this holder 3 is provided with a water passage 4 therethrough and has an internally screw-threaded portion 5 at the end opposite the brush 1.

A hollow spindle 6 receives in its upper end a slidably mounted reciprocating tubular support or plunger 7. This plunger 7 is provided with an elongated slot 7' in its lower portion through which passes the removable pin 8 engaging in the spindle 6 and the engagement of the pin 8 in the slot limits the upward movement of the plunger 7 by contact with the lower closed end of the slot. The pin 8 limits the upward and downward movement of the plunger 7 and secures the same within this spindle 6. By removing pin 8, the plunger 7 may be detached from the spindle 6 when desired.

The upper end of the plunger 7 is screw-threaded externally to receive the threaded portion of the brush-holder 3, which is thus removably mounted thereon and may be readily detached to replace a worn brush with a new one or for purposes of repair.

Surrounding the plunger 7 is a spring 9, one end of which abuts against a collar 10 formed externally on the plunger 7, and the other end rests upon the upper end of spindle 6. The action of this spring 9 is to continually and to positively force the tubular plunger 7, and hence the brush supported thereby, upwardly to the limit of its movement, as regulated by the pin 8 traveling in slot 7' of the plunger.

As the brush carried by the reciprocating plunger 7 becomes worn and shortened by constant usage, the spring 8 compensates for this wear and insures the proper contact of the brush with the bottom of the bottle being cleaned. It is clear that in the ordinary bottle washing machine wherein the bottles receive a predetermined and limited movement, and the brushes are given simply a rotative movement, through constant use the brushes will become so worn as to no longer touch the bottoms of the bottles and thorough cleaning will not be effected. By the construction herein described this disadvan-

tage is removed and the effectiveness of this class of machines improved.

In Fig. 1 I have shown my improved spindle in use in a bottle washing machine of a well known type, sufficient parts of the machine only being shown to illustrate the operation. The spindle 6 is mounted for rotation, being driven through gear 11 mounted on the base plate 12 of the machine. The brush 1 carried by the spindle 6, when the machine is not operating, rests within the sleeve 13 of the lower bottle supporting plate 14. The plates 14 and 15 receive the bottle 16 therebetween. The bottle 16 is clamped between the plates 14 and 15 by operating a suitable lever 17 mounted on the shaft 18 and secured to plate 15, which forces plate 15 downwardly into contact with the bottle and locks it in this position. Both plates 14 and 15 are mounted for reciprocation on guide 19 by means of collars 20 and 21 respectively. These plates 14 and 15 constitute the bottle carrier and are given a vertical reciprocatory movement in any well known manner through the medium of the operating crank 22 and the rod 23. To the rod 23 is connected a collar 24 which engages the plate 15, while the collar 20 of plate 14 is provided with an extension 25 connected to the rod 23. The bottle carrier receives a limited downward movement through the crank 22 and rod 23, which carries downwardly the sleeve 13, thereby liberating the brush 1 and bringing the interior of the bottle into contact therewith. In the lowered position of the carrier, the bottle bottom presses against the brush 1 and acts against the pressure of spring 9 so that good contact between the bottle bottom and brush is secured. The brush 1 being spring pressed

thus constantly assumes the best and most effective operative relation to the interior of the bottle in spite of any wear that may be occasioned by constant use.

Other means of accomplishing the objects of my invention may be suggested by this description of the preferred embodiment thereof, and various changes may be introduced to attain these ends, but are believed to fall within the scope of this invention.

What I claim and desire to secure by Letters Patent of the United States, is:—

1. In a bottle washing machine, a rotary spindle, a reciprocating member mounted therein, having a slotted lower portion, a removable brush holder secured to said member, a resilient means mounted upon the spindle and engaging the reciprocating member, providing a yielding support for the brush holder, and removable means engaging in said slotted portion to limit the movement of the reciprocating member, substantially as described.

2. In a bottle washing machine, a rotary spindle, a tubular support mounted for reciprocatory movement therein, and having a vertical slot, a brush holder removably mounted thereon and provided with a brush, means for limiting the movement of the support, engaging in the slot thereof and a spring carried on the spindle and engaging the support and normally acting to hold the latter at the limit of its upward movement, substantially as set forth.

In witness whereof I hereto affix my signature in presence of two witnesses.

EDWARD COURT.
